LATRINE-INCINERATOR.

1,069,962.

Specification of Letters Patent.

Patented Aug. 12, 1913.

Application filed January 6, 1911. Serial No. 601,128.

To all whom it may concern:

Be it known that I, EDWARD C. LEWIS, a citizen of the United States, residing at Chicago, county of Cook, and State of Illinois, have invented certain new and useful Improvements in Latrine-Incinerators, of which the following is a specification.

My invention relates to latrine incinerators, and constitutes an improvement over the apparatus which was described and claimed in my co-pending application, Serial Number 591,824, filed November 11, 1910.

The construction which was described in the last-mentioned application was such that the excreta were scraped from the bowl into the furnace or incinerator, where such excreta are burned and the blades of the scraper sterilized. In the construction which forms the subject-matter of the present application the excreta are delivered to the furnace by swinging inwardly a plate which forms the bottom of the bowl, thus throwing the excreta upon the bed of fuel and sterilizing the movable bottom plate of the bowl. This mechanism is preferably operated by means of the cover, in connection with which an extension is provided, which is connected by means of a link with the movable bottom plate. It will be clear to those skilled in the art that this construction has the advantage of great simplicity and little liability for the necessity of repairs.

These and other advantages of my invention will be clearer by reference to the accompanying drawings, which represent a preferred embodiment of my improvements, and in which—

Figure 1 is a plan view showing the incinerator or furnace with the bowls connected therewith; Fig. 2 is a vertical section through one of the bowls, taken on the line 2—2 of Fig. 1, the cover being shown in elevated position; and Fig. 3 is a vertical section similar to Fig. 2 except that the cover is shown as closed.

A plurality of latrines 10 are connected with a furnace 11, which may be of any desired construction. In the drawings I have shown three latrines; but my invention is equally applicable where but a single latrine or any desired number are used. The incinerator 11 has a central opening 12 in

its top, and on one side is provided with a fire door of the usual construction.

Each of the latrines 10 comprises a bowl 13 which is preferably made integral with the seat 14. The bowl 13 is also provided with a movable bottom plate 15, which is pivoted at 16 and provided with a shallow central groove 17. The pivotal connections 16 operate within the slots 18 in the sides of the bowl 13. The bottom plate 15 is also supported by means of the lugs 19.

The cover 20 is pivoted at 21 and provided with the extension 22 which is connected with the bottom plate 15 by means of the links 23 and forms the rear side wall of the bowl. When the bottom plate 15 is in the position shown in Fig. 2, its upper edge 23^a abuts against the downwardly extending rib or flange 24, which is preferably made integral with the bowl 13. The inside of the bowl 13 is in direct communication with the inside of the incinerator 11.

Having thus described the construction of the various parts used in my invention, its operation may now be readily understood. When one of the latrines 10 is to be used, the cover 20 is raised and the parts assume the positions shown in Fig. 2, the excreta being caught on the bottom plate 15. When the cover 20 is closed, the bottom plate 15 is first moved to the right, until the pivotal connections 16 reach the right-hand ends of the slots 18. As the cover 20 continues to be lowered, the extension 22 is of course correspondingly raised, and the links 23 then operate to swing the bottom plate 15 upwardly until it assumes the position shown in Fig. 3. In this way the excreta are thrown upon the bed of fuel within the incinerator or furnace 11. An examination of Figs. 2 and 3 will demonstrate that when the cover 20 is raised, the opening between the interior of the bowl 13 and the inside of the incinerator 11 is substantially closed by the extension 22, whereas when the cover 20 is closed, the same opening is substantially closed by the bottom plate 15.

In this way the access of excessive heat to the inside of the bowl 13 is prevented, and also the passage of a draft between the inside of said bowl and the inside of the incinerator. When the bottom plate 15 is in the position shown in Fig. 3, it is subjected to the action of the hot gases within the incinerator 11,

and in this way becomes perfectly sterilized. When the cover 20 is again raised, the extension 22 is of course lowered, thereby lowering the bottom plate 15 until it rests 5 on the lugs 19. On raising the cover 20 still farther, the bottom plate 15 is moved to the left, forming a close connection between its upper edge 23^a and the edge of the flange 24, which preferably has an overhanging 10 lip 24^a.

It will be apparent to those skilled in the art that many changes could be made in the detail construction of the parts which I have described without departing from the spirit 15 or scope of my invention.

What I claim is:

1. In a latrine incinerator, a furnace, a latrine having a movable false bottom adapted to turn on one edge thereof for receiving 20 the excreta, and means for actuating said bottom whereby the excreta are deposited in the furnace, said bottom-actuating means operating to normally close off the latrine from the furnace and also to automatically 25 remove such closure when the bottom is actuated, substantially as described.

2. In a latrine incinerator, a furnace, a latrine arranged laterally thereof, a movable bottom having a hinge-like connection with 30 said latrine on the side next the furnace, said bottom adapted to receive excreta, and means for lifting said bottom on said connection whereby the excreta are transferred laterally to said furnace, said bottom-actuating 35 means operating to normally close off the latrine from the furnace and also to automatically remove such closure when the bottom is actuated, substantially as described.

3. In a latrine incinerator, a furnace, a latrine connected at its rear with said furnace, a movable bottom pivoted at one edge thereof to said latrine, said bottom adapted to receive excreta, and means for lifting the 45 front of said bottom whereby the excreta are transferred to the rear to said furnace and the opening between said latrine and said furnace is substantially closed, said bottom-actuating means operating to normally close 50 off the latrine from the furnace and also to automatically remove such closure when the bottom is actuated, substantially as described.

4. In a latrine incinerator, a furnace, a latrine connected with said furnace, a movable bottom having pivotal connection at one edge with said latrine, said bottom adapted to receive excreta, and means for swinging said bottom upwardly on said pivotal 55 connection whereby the excreta are transferred laterally to said furnace and the opening between the latrine and the furnace is substantially closed by said elevated bottom, said bottom-actuating means operating to normally close off the latrine from the furnace 60

and also to automatically remove such closure when the bottom is actuated, substantially as described.

5. In a latrine incinerator, the combination of a furnace, a latrine communicating laterally with the inside of said furnace, a movable bottom and a movable side wall for said latrine, said bottom in its normal position adapted to receive excreta and said side wall to close the communication between the latrine and the furnace, means for moving said bottom into the position formerly occupied by the side wall whereby the excreta are transferred to said furnace and the movable bottom exposed to the heat of the fur- 70 nace. 75

6. In a latrine incinerator, the combination of a furnace, a latrine connected with the inside of said furnace, a movable bottom for said latrine, said bottom in its normal position adapted to receive excreta, means for substantially closing the opening between said latrine and said furnace when said movable bottom is in its normal position, and means for simultaneously actuating said bottom and said closing means whereby the excreta are transferred to said furnace, the closing means removed from the opening between the latrine and the furnace and said bottom is brought into position to substantially close said opening, sub- 80 stantially as described. 90

7. In a latrine incinerator, the combination of a furnace, a latrine having a projecting rib on its interior, a tilting and sliding bottom in said latrine for receiving excreta, one edge of said bottom normally extending beneath said rib, and means for removing said bottom from beneath said rib and then tilting the same, whereby the excreta are 100 transferred to said furnace, substantially as described. 105

8. In a latrine incinerator, the combination of a furnace, a latrine, a bottom plate having sliding pivotal connection with said latrine, and means for first moving said bottom plate on said sliding connection and then swinging said plate, whereby the excreta are transferred to said furnace, sub- 110 stantially as described. 115

9. In a latrine incinerator, the combination of a furnace, a latrine having grooves in its sides, a movable bottom plate having pivotal engagement with said grooves, said plate adapted to receive excreta, and means for first moving said bottom plate in said 120 grooves and then swinging said plate, whereby the excreta are transferred to said furnace, substantially as described.

10. In a latrine incinerator, the combination of a furnace, a latrine having grooves in its sides and a projecting rib on its interior, a movable bottom plate normally having engagement with said rib and having pivotal connection with the grooves in 125 130

5 said latrine, said plate adapted to receive excreta, and means for actuating said bottom plate whereby the latter is first withdrawn from its engagement with said rib and then swung upwardly, whereby the excreta are transferred to said furnace, substantially as described.

10 11. In a latrine incinerator, the combination of a furnace, a latrine connected laterally with said furnace, a removable closure between the latrine and furnace, a movable bottom in said latrine, said bottom adapted to receive excreta, a cover for said latrine, and a connection between said cover and closure and said movable bottom whereby, when the cover is closed, said closure will be removed and said movable bottom will be lifted to transfer the excreta laterally to said furnace, substantially as described.

15 12. In a latrine incinerator, the combination of a furnace, a latrine connected laterally therewith, a movable bottom in said latrine, said bottom adapted to receive excreta, a cover for said latrine, said cover having an extension thereon forming a removable closure between the latrine and furnace when the cover is open, and means connecting said extension with said movable bottom whereby, when said cover is closed, the closure will be removed and said bottom will be moved thereby transferring said excreta laterally to said furnace, substantially as described.

20 13. In a latrine incinerator, the combination of a furnace, a latrine connected with said furnace, a movable bottom, said bottom adapted to receive excreta and having pivotal connection with said latrine, a cover having an extension projecting into the opening between said latrine and said furnace when the cover is raised, and means connecting said extension and said movable bottom whereby, when the cover is closed, said extension is removed from the opening between said latrine and said furnace and said movable bottom is swung upwardly, thereby transferring said excreta to said furnace and closing the opening between said latrine and said furnace, substantially as described.

25 14. In a latrine incinerator, a furnace, a plurality of latrines connected laterally with said furnace, a movable bottom in each of said latrines and having pivotal connection therewith, and means for tilting said bottom from a horizontal to a vertical position whereby the excreta are transferred to said furnace and the opening between

30 said latrine and said furnace is substantially closed, said bottom-actuating means operating to normally close off the latrine from the furnace and also to automatically remove such closure when the bottom is actuated, substantially as described. 60 65

15 15. In a latrine incinerator, the combination of a furnace and a latrine arranged side by side in communication through a lateral opening, the latrine having a bottom and a lateral closure hinged respectively below and above on that side adjacent the furnace and connected one to the other, means connected to one of the hinged members whereby to cause the said members to assume a relative perpendicular position and to occupy alternatively the one a horizontal and the other a vertical position, substantially as described. 70 75

16. In a latrine incinerator, the combination of a furnace and a latrine arranged side by side in horizontal open communication through a lateral opening, the latrine having a false bottom and a lateral closure hinged on that side adjacent the furnace and respectively below and above the communicating opening, said false bottom and lateral closure also connected one to the other and the latrine cover connected to the closure whereby to cause the said hinged members to assume a relative perpendicular position and to occupy alternatively the one a horizontal and the other a vertical position, substantially as described. 80 85 90

17. In a latrine incinerator, the combination of a furnace and a latrine arranged side by side in communication through a lateral opening, the latrine having a bottom and a lateral closure hinged respectively below and above on that side adjacent the furnace and also one to the other, means connected to one of the hinged members whereby to cause the said members to assume a relative perpendicular position and to occupy alternatively the one a horizontal and the other a vertical position, an overhanging rib formed on the true bottom of the latrine, and the hinge connection of the false bottom providing for lateral play whereby the bottom is slid horizontally from beneath the overhanging rib and then swung to a vertical position, substantially as described. 95 100 105 110
